[57] CLAIM

The ornamental design for a combined clinical-chemical analyzer evaluation unit and work station, as shown and described.

DESCRIPTION

FIG. 1 is a perspective view of a clinical-chemical analyzer evaluation unit, showing my new design, with cover removed;

FIG. 2 is a side perspective view thereof, with cover attached;

FIG. 3 is a front elevational view thereof;

FIG. 4 is a side perspective view thereof, opposite that shown in FIG. 2;

FIG. 5 is a rear elevational view thereof;

FIG. 6 is a bottom plan view thereof;

FIG. 7 is a perspective view of a work station;

FIG. 8 is a side perspective view thereof;

FIG. 9 is a side perspective view thereof, opposite that shown in FIG. 8;

FIG. 10 is a rear elevational view thereof;

FIG. 11 is a top plan view thereof;

FIG. 12 is a bottom plan view thereof; and,

FIG. 13 is a perspective view of the combined clinical-chemical analyzer evaluation unit and work station with the cover removed on the analyzer.
